UNITED STATES PATENT OFFICE.

ISAAC W. HEYSINGER, OF PHILADELPHIA, PENNSYLVANIA.

DISCHARGING MECHANISM FOR SYRUP OR OTHER JARS.

SPECIFICATION forming part of Letters Patent No. 642,119, dated January 30, 1900.

Application filed April 23, 1898. Serial No. 678,663. (No model.)

To all whom it may concern:

Be it known that I, ISAAC W. HEYSINGER, a citizen of the United States, residing at Philadelphia, in the county of Philadelphia and State of Pennsylvania, have made a certain new and useful Improvement in Discharging Mechanism for Syrup or other Jars and the Like, of which the following is a full, clear, and exact description, reference being had to the drawings which accompany and form a part of this specification, in which—

Figure 1 is a vertical section from front to rear through the middle of a syrup-jar embodying my improvement. Figs. 1^a, 1^b, and 1^c are enlarged views showing slight mechanical modifications in the drip-stops which I prefer to use. Fig. 2 is a horizontal section along the dotted line *x x* of Fig. 1 looking downward on the bottom of the jar. Fig. 3 is a transverse vertical section along the dotted line *y y* of Fig. 1. Fig. 4 is a view, similar to Fig. 1, of the operative parts of my invention, showing a slightly-different arrangement of the discharge-pipe *D* and in which 25 a positive instead of a spring thrust causes the retraction of the piston or plunger within the force-chamber. Fig. 5 is a view similar to Fig. 4, in which instead of a push-button merely a lever-handle is used to force down 30 the plunger and retract the same. Fig. 6 is a view similar to Fig. 1, in which instead of a force-chamber of cylindrical form a soft-rubber hemisphere or the like open beneath is used and a plunger above it to compress 35 the same. Fig. 7 is a view similar to Fig. 1, in which the plunger is made solid and the vent-pipe for the syrup is carried from the force-chamber independently of the plunger and stem; and Fig. 8 shows my invention in 40 which the jar is mounted upon skids instead of having side supports integral with the said jar and in use in a soda-water apparatus.

The lettering in all the figures is uniform.

My invention relates to mechanism for the 45 discharge of syrups or the like from stationary jars or other receptacles into glasses or other vessels, as is customary in soda-water apparatus; and it consists in forming the jar or receptacle solid—that is to say, with closed 50 sides and bottom and without any syrup-vent beneath—and in raising the syrup by pres-

sure above the top of the jar and thence discharging the same into tumblers or the like, as may be desired; and it consists in providing such solidly-walled jar with a recess in 55 the bottom thereof to form a collecting-cavity and having preferably sloping sides and providing for this recess an adjustable forcing-chamber and plunger so constructed that when slightly raised the syrup will flow into 60 said collecting cavity or recess beneath the sides of said forcing-chamber contained therein, and when the said plunger is forced down contact will be first made between the margins of said chamber and the bottom of said 65 recess, and as the descent of the handle and plunger continues the fluid contained in said chamber will be forced upward through a suitable tube provided therefor and over the upper margin of said syrup or other jar—that 70 is, above the level of the fluid contained therein—and, when the plunger is raised again, that, at the same time the margins of said chamber will be lifted from the bottom of said recess, and the same will refill so long as any 75 fluid remains in said jar.

It will be seen that, in my invention, I use mechanism which will collect into a recess a limited supply of syrup from the jar, and in this I provide a forcing-chamber open below 80 and a plunger, so that I can close thereby connection between the mass of syrup in the said jar and the limited quantity held in said forcing-chamber, and I then force the same by pressure applied to said plunger through a 85 suitable exit-pipe up and over the upper margin of said jar or above the level of the fluid contained therein, the size of the forcing-chamber thus graduating the quantity to be forced out at each reciprocation of said plunger, which enables the syrup to be accurately 90 measured as it is drawn.

Another advantage is that there are no cocks or faucets to become leaky at the bottom of the jar, so as to waste the syrup or else flood 95 the counter with syrup accidentally leaking from an unclosed faucet, while by the use of my invention I am enabled to place my syrup-jars down at the bottom of a soda-water apparatus, where they ought to be to receive the 100 full benefit of the ice, and the ice-space is correspondingly enlarged by these jars being

thus at the bottom instead of midway or even at the top, as in many soda-water-supplying devices in general use.

In the ordinary soda-water apparatus as used in drug-stores, &c., the front and bottom parts of the interior are absolutely useless, being a mere vacant space beneath the elevated row of syrup-jars, and this becomes not only a waster of ice, but a source of dampness and dirt.

In my invention the row of jars rests practically at the level of the counter upon which the apparatus stands, with only enough space beneath to insure non-conduction of heat.

15 My invention also relates to devices for preventing drip after a glass of syrup has been drawn and to preventing ingress of insects or dirt to the nozzle thereof.

Referring to the drawings, A, Fig. 1, is a 20 rectangular jar longer from front to rear, though the shape is not material, and constructed of glass, porcelain-lined metal, or the like and having an opening in the top, (shown at A³, Fig. 1,) the remainder of the jar having closed walls throughout. Instead of this opening A³, the whole top of the jar may be left open, of course provided a larger cover be used; but I prefer for convenience in handling to have it in the form shown. As shown 25 at B, Figs. 1 and 3, in the forward side of the bottom I form a recess A', preferably circular in form, as shown at Fig. 2, and with inwardly-sloping sides from above downward. The bottom of the jar A', Figs. 1, 6, and 7, I also 30 slightly incline forward, so as to insure the drainage of the syrup into the recess A' when the jar is nearly empty. To support the jar, by reason of this recess A', I provide it with side extensions B B, by means of which the jar 35 will stand erect or may be slid in or out of its receptacle in a soda-water apparatus. In Fig. 4 instead of these side extensions of the jar I show skids B' B', attached to the syrup-jar holder of the soda-water apparatus, and in 40 this figure I show two of these jars in place, which skids sustain the jars in position therein. When what are called "tipping" jars are used—that is to say, jars which tip forward at the top to be filled without removal from 45 the apparatus—I prefer to use the form of jars shown in Fig. 8, but with the skids B' B' replaced by the socketed front support B², as shown in Fig. 5, whereby the jar can be tilted forward at its upper part, so as to expose the 50 top of the jar and permit the removal of the discharging mechanism and refill the jar while still in place in the apparatus, the proportions being suitably conformed thereto, as with the present covers of tipping jars.

60 The opening A³, Fig. 3, of the jar A is closed by the detachable cover C, which may be of wood, vulcanite, or metal. As shown in Fig. 3, it has small flanged lips c c, which secure it in place, and, as shown in Fig. 6, it may be 65 circular, if desired, and screwed fast into the opening A³, the same then being also circular and screw-threaded. Ordinarily I hold it in

place, as shown in Fig. 1, by the turn-button or other fastening C'. This cover C is provided with a hole C² for the handle-stem and 70 also with a hole at its front margin C³ for the discharge-pipe; but when, as shown in Figs. 4, 5, and 6, the discharge-pipe passes up as a part of the handle-stem a single hole C² will be sufficient.

75 In the preferably-tapered recess A' of the jar A sets a hollow cylindrical pressure-cup or forcing-chamber, which fits when pressed down upon the bottom of the recess A' or else in contact with its sloping sides and 80 makes a sealed joint to prevent egress of the contained fluid. When raised slightly, the fluid again flows in from the jar and fills this recess and the cup or chamber. As shown in Fig. 1, this cylindrical forcing chamber or 85 cup F is covered over above with the perforated cover pierced with exit-holes f f to permit the fluid above the plunger to flow out when the said plunger has been raised. The plunger D³ fits this forcing-cylinder like a 90 piston and at its middle has a hole which opens into and forms the inlet of a vertical discharge-pipe D, rigidly secured thereto, so that when the forcing-chamber is pressed down and the plunger then descends the contained fluid will be forced upward through the pipe D and thence outwardly over the 95 margin of the jar A to its discharge-exit D², where it may be caught in a tumbler placed underneath and adjacent to the face of said 100 jar.

To insure the consecutive movements of the plunger and forcing-chamber, I provide the handle E at the top of the stem E', which passes down vertically to the plunger D³, to 105 which it is attached. A coiled spring E², Figs. 1, 6, and 7, maintains this handle in an elevated position, so as to hold up the bottom margins of the forcing-chamber F from contact with the recess A'. A coiled spring D⁷ 110 beneath the cover C bears beneath upon the collar F' of the forcing cup or chamber F and above against a collar d upon the plunger-stem D E', so that the plunger D³ is constantly retracted to the upper part of the chamber F 115 except when forced down against the tension of this spring D⁷ by pressure upon the handle E. In Figs. 4 and 5 instead of the spring D⁷ I use one or two rods attached below to the top of the forcing-chamber F and at their upper ends passing through perforations in the cover C, and to enable the downward movement of the plunger D to carry down the forcing-chamber F, I make a sliding friction-joint between the plunger D and the neck F' 120 of the forcing-chamber F, as shown in Fig. 5. These rods are lettered D⁸ D⁹ and are provided with collars d⁸ d⁹, Figs. 4 and 5, which may be made vertically adjustable, if desired. These collars d⁸, striking against the under 125 side of the cover C, arrest the upward motion of the forcing-chamber at a proper height, while the spring E² continues the ascent of the plunger D³ in the chamber F.

In Fig. 5 instead of using the coiled spring E², I operate the tube D by means of a pivoted lever E⁵, pivoted to D at e and to the cover C at C⁴, and use the hinge-spring E³ to hold the lever-handle E⁴ elevated against pressure.

The inside of the collar F', as shown at Fig. 2, I prefer to make, when thick syrups are used, with vertical flanges around the tube D to prevent sticking from crystallization of the syrup. The lever-handle E⁵ E⁴ (shown in Fig. 5) may be used with the devices shown in all the other figures, if desired.

In Fig. 6 instead of a rigid forcing-chamber F, I use a collapsible elastic rubber cup F², open beneath, perforated at its center for the discharge-pipe D, and secured to the lower end of the same. Above it is the flat plunger or rigid portion F³, the purpose of which is to compress the top of the pressure-chamber and so eject the fluid through the tube D and the discharge-nozzle D².

In Fig. 7 I use a mechanism similar to that shown in Fig. 1, except that the plunger-stem E¹ is solid, the plunger D⁴ is without a perforation, and the discharge-pipe D⁵ is carried up directly from the bottom of the recess A', so that it does not rise and fall with the movements of the plunger, but is fixed with reference to the jar A. The springs E² and D⁷ have the same functions as in Fig. 1.

In Figs. 1^a, 1^b, and 1^c I show the means which I prefer to use to prevent drip from the discharge-nozzle D² or the entrance of insects or dirt thereto. In Fig. 1^a is shown a cylindrical plug E⁴, which occupies the bore of the tube D and reciprocates therein across the discharge-opening D². It is connected with an arm E³, which is pivoted at C⁵ by means of the pivot e' to the top of the fixed cover, so that as the handle E is depressed, carrying with it vertically the tube D, the arm E³ will thrust forward the sliding plug E⁴ within the tube D and uncover the vent D². When the handle E again rises, it will draw back the plug E⁴ over the vent D² and again close the same. In Fig. 1^b the same devices are shown, excepting that instead of an internal plug E⁴ an external sleeve E⁵ is used, which opens and closes the exit-opening D² in the same manner.

In Fig. 1^c an internal plug E⁴¹ is employed, as in Fig. 1^a; but this is connected to a stem E⁶, supported by a coiled spring e⁶, and the inward force of the fluid compresses this spring and opens the vent, which again closes when pressure has been removed from the handle E. The form shown in Fig. 1^c is especially adapted for use with the modification shown in Fig. 7.

In Fig. 1 I have indicated the use of the form shown in Fig. 1^a.

While I show these various devices hereinabove described as in use together in my improved discharging mechanism for syrup-jars and the like, I do not always use all these devices together, and I also vary the same to

conform to special applications and requirements as would be done to meet such conditions by any skilled mechanic and without departing from the principles of my invention as herein shown, described, and claimed.

Having now described my invention, what I claim, and desire to secure by Letters Patent, is—

1. In discharging mechanism for syrup-jars and the like, in combination with a jar having closed sides and bottom, and a vertical recess with tapered sides formed in said bottom, a cup-shaped forcing-chamber open beneath and adapted to be loosely guided by and seated in said recess, a handle above said forcing-chamber projecting above the top of said jar, adapted to operate the same, together with a discharge-pipe leading from within said forcing-chamber and recess upward, and provided with an overhanging discharge-nozzle above the surface level of fluids contained in said jar, and means operatively connected with said handle and stem for compressing the fluid in said forcing-chamber, and causing its discharge through said pipe and nozzle, and means for subsequently raising said forcing-chamber from the bottom of said recess, so as to admit a new supply of said fluid from said jar, into said forcing-chamber, substantially as and for the purposes described.

2. In combination with a jar open at top and having closed sides and bottom, and having a vertical recess in said bottom opening upwardly, a reciprocative forcing-chamber loosely fitted in said recess, and open beneath, said forcing-chamber adapted, when slightly raised to admit fluid from said jar at the bottom of said recess and into the same, and when forced down to make a sealed joint between said fluid in said forcing-chamber and said fluid in said jar, and means to compress the fluid in said chamber, together with an exit-pipe for said fluid, leading upwardly and above the level of the fluid in said jar, and adapted to discharge the contents of said forcing-chamber from said jar, and a handle operatively connected with said forcing-chamber and compressor, to operate said chamber to make said sealed joint, and afterward, by continuous pressure, force said contained fluid through said exit-pipe and discharge the same from said jar, substantially as and for the purposes described.

3. In combination with a jar having an opening above, and closed sides and bottom, and a flat-bottomed recess with sloping sides in said bottom, and a reciprocative cylindrical forcing-chamber, open beneath, fitted to said recess, and guided downward to the bottom thereof by said sloping sides, and adapted, when slightly raised, to present an opening between the sides of said recess and the bottom of said forcing-chamber, and a plunger operating in connection with said forcing-chamber, together with a vertical stem above said plunger, and secured thereto, and extended above the level of fluid contained in

- said jar, and a handle for operating the same, and means for retracting said plunger from said forcing-chamber and subsequently re-tracting said forcing-chamber from said recess, and an exit-pipe therefrom, extended above the level of the fluid containable in said jar, and adapted to discharge the same when pressure is applied to said handle, substantially as described.
- 10 4. In discharging mechanism for syrup-jars and the like, in combination with a jar having an opening above, and with closed sides and bottom, and having a recess in said bottom at the forward side of said jar, and a slightly-sloping bottom adapted to cause fluid to flow, by gravity thereto, a reciprocative cylindrical forcing-chamber loosely fitted to said recess when slightly raised therein, said chamber open beneath, and provided with a plunger 15 adapted to vertically reciprocate therein, and an exit-pipe extended above said jar and adapted to discharge its contents laterally over the top thereof, together with a stem and handle operatively connected therewith, and 20 a spring adapted to retract said plunger in said chamber, and means for subsequently retracting said forcing-chamber from the bottom of said recess, substantially as and for the purposes set forth.
- 25 5. The combination of a jar open above and having closed sides and bottom, and a recess in said bottom having a flat bottom and sloping sides, a cylindrical cup-shaped forcing-chamber slightly reciprocative in said recess, a plunger reciprocative in the cylinder of said chamber, a tube attached to the middle of said plunger, and forming an exit-pipe from said chamber, a handle above said tube and above the level of fluid containable in said jar, and 30 said exit-pipe having a discharge-nozzle above the level of the top of said jar, together with means for retracting said plunger in said chamber and also for retracting said chamber in said recess, substantially as described.
- 35 6. The combination of a syrup-jar with closed bottom and recess therein, a cylindrical forcing-chamber reciprocative therein, a centrally-perforated-plunger reciprocative in said chamber, an exit-tube secured to and 40 continuous with said perforation in said plunger, an operating-handle at top of said tube, and exit-nozzle above top of said jar continuous with said tube, together with means for causing said plunger to reciprocate in said chamber and said chamber in said recess by continuous downward pressure of said tube or handle, substantially as described.
- 45 7. In combination with jar, A, having recess, A', and opening, A³, above the same, the cylindrical forcing-chamber, F, reciprocative in said recess, the reciprocative plunger, D³, in said chamber, the tube, D, leading from said chamber, F, through said plunger, D³, and secured thereto to operate the same, the discharge-nozzle, D², above the top of said jar, and a lever-handle, E⁵, operatively connected with said exit-tube D, together with a spring 50 adapted to operate the same, substantially as and for the purposes described.
- 55 8. In a soda-water apparatus a series of jar supports at bottom of the same, and in combination therewith a series of syrup-jars, said jars having closed sides and bottoms, and upwardly-opening recesses within said jars, and with forcing-chambers reciprocative in said jars and recesses, and with exit-pipes connected therewith and adapted to discharge over the tops of said jars, and a series of handles extended above said jars and operatively connected, one with each of said forcing-chambers, and with means for compressing the fluid in said forcing-chambers and causing it to ascend through said pipe and be discharged over the top level of the fluid in said jar, and with means operatively connected with said handles to retract said chambers in said recesses, substantially as described.
- 60 9. In a syrup-discharging mechanism, a jar having closed sides and bottom, an upwardly-opening tapered recess in the said bottom, and a vertically-reciprocative and loosely-fitting forcing-chamber of definite capacity guided by the tapered sides of said recess, a plunger operating in said chamber reciprocatively, an exit-pipe, adapted to discharge upwardly and outwardly over the top of said jar, a handle adapted to reciprocate said chamber in said recess, and said plunger in said chamber, so that, at each reciprocation, a graduated quantity of said syrup shall be taken from the contents of said jar, and forced upward through said exit-pipe, together with means for retracting said chamber and said plunger, after said reciprocation thereof, substantially as described.
- 65 10. In combination with the jar, A, having closed sides, and recess in its bottom, A', the cover, C, cylindrical forcing-chamber, F, plunger, D⁸, perforated at center and communicating with exit-pipe, exit-pipe, D, discharge-nozzle, D², retracting-spring to retract the said forcing-chamber, and handle for operating the same, substantially as described.
- 70 11. In combination with jar, A, discharge mechanism, D⁸ F, A', exit-pipe, D, and handle adapted to vertically reciprocate said exit-pipe D, an arm, E³, secured, at C³, to the fixed cover, C, and drip-plug, E⁴, adapted to cover discharge-nozzle, D², and to be pushed away from same when said exit-pipe is depressed and the discharge of the contained fluid thereby effected, substantially as described.
- 75 12. In a syrup-discharging mechanism, in combination with a vertically-reciprocative exit-pipe, adapted to be depressed to cause the discharge of syrup from the same, a slide adapted to normally close the discharge-nozzle of said reciprocative pipe, and constructed to be pushed aside, when the discharge takes place, by means of an operative arm connected therewith, said arm supported at its opposite end on the fixed part of said mechanism substantially as described.

13. In syrup - discharging mechanism, in combination with the discharging-nozzle of a syrup-exit pipe, a slide adapted to normally close said nozzle, and to be forced therefrom during the discharge of said syrup, together with a spring or its equivalent for operating said slide, substantially as described.

14. In combination with a soda-water apparatus, a series of syrup-jars arranged along the same at the base or bottom part of said apparatus, said jars having closed bottoms, and tops open upward, and said open tops closed by detachable covers fitted thereto, and in combination with said covers, and supported thereby, a syrup - forcing apparatus operatively connected with the inside of each

of said jars, with operating-handles supported by said covers and extended above the same, and discharge-pipes for said syrup extended upward from the lower portions of and within said jars, operatively connected with said forcing apparatus, and adapted to discharge the syrup, under pressure thereof, upwardly and thence over the tops of said jars, and into portable receptacles supported under the discharge-outlets of the same, substantially as described.
